UNITED STATES PATENT OFFICE.

ADONIRAM J. SMITH, OF SEATTLE, WASHINGTON.

LETTER-BAG ATTACHMENT.

1,099,518.

Specification of Letters Patent.

Patented June 9, 1914.

Application filed January 15, 1914. Serial No. 812,177.

To all whom it may concern:

Be it known that I, ADONIRAM J. SMITH, a citizen of the United States, residing at Seattle, in the county of King and State 5 of Washington, have invented certain new and useful Improvements in Letter-Bag Attachments, of which the following is a specification.

This invention relates to means for attaching packages of mail matter to letter-carriers' bags; and has for its object to provide a novel device which may be conveniently applied or removed from a letter-bag and when in position will afford a reliable 10 support for articles upon the outside of the bag and obviate the necessity of encumbering the bag receptacles with packages or bundles of mail matter.

The invention consists in the novel construction and combination of parts, as will be hereinafter described and claimed.

In the accompanying drawings, Figure 1 is a perspective view of the improved package support shown applied to a letter-carrier's bag; and Fig. 2 is a detail sectional view taken substantially through 2—2 of Fig. 1.

The letter-bag, as shown in Fig. 1, is or 30 may be of the ordinary form and, as shown, is constructed with a front wall 5, a rear wall 6, a gore-piece 7 at each end, and a flap 8 connected to the rear wall and utilized as a cover for the mouth in wet or rainy weather. At each side is a reinforcing strap 35 9 connecting the front and back walls. 10 represents a partition to divide the bag into two compartments 11 and 12 which are usually employed as receptacles for mail received and mail delivered in the carrier's 40 route.

According to the present invention, I provide a hanger 13 constituted of a piece of wire having a horizontal portion 14 which is formed to the curve of the bag's front wall 45 5. Centrally of its length the wire is formed with a loop 15 to receive the eye 16 of a suspending hook 17 and at its ends the wire is bent upwardly, as at 18, and formed into suspending hooks 19. Said hooks are 50 signed to engage over the top of the bag-wall 5 and terminate in forwardly directed

ends 20 which extend through holes 5¹ provided in the bag-wall, as best shown in Fig. 2. By such devices, the hanger is supported upon the bag's front wall and is secured thereto against accidental displacement by the hook extremities 20 engaging in the holes 5¹. To remove the hanger, the hook portions, as 17¹, to the rear of the referred to wall, are sprung rearwardly to disengage 60 the hooks from the wall, whereupon the hanger may be raised clear of the bag. Fasted to the hanger-part between the suspending hooks therefor is a plurality of hooks 21 to which packages may be attached, as indicated by dotted lines A in Fig. 1. The hooks 21 are desirably made of spring wire and are connected with the hanger by eyes 22 formed on the hooks so that the same will not be detachable but 70 shiftable sidewise along the hanger-part 14.

Supplemental to the aforescribed parts, hooks 23 are desirably connected to the straps 9, and to prevent the hooks from undue vibratory or swinging movements, tie-chains such as 24 connect the same with loops 25 provided in the adjacent ends of the hanger.

In practice, it is found advantageous to hang the heavier or more bulky packages 80 from the hooks 23 at the bag ends.

From the foregoing it will be seen that the bag attachment for carrying mail matter is inexpensive to manufacture, is sufficiently strong, light, easily applied and removed, and furnishes a great convenience to the letter-carrier by enabling him to take a larger load than hitherto possible in a single bag and without interfering with the obtaining of letters from the interior of the 90 bag.

What I claim as my invention, is—

1. A letter-bag attachment, comprising a hanger provided with hooks for detachably connecting the same to a bag, and means 95 supported by said hanger for suspending packages therefrom.

2. A letter-bag attachment, comprising a hanger having hooked ends which pass over the top of the bag-wall and engage in holes 100 provided in the latter, and package-engaging hooks connected to said hanger.

3. A letter-bag attachment, comprising a
hanger engageable with a mail-bag, pack-
age-supporting hooks suspended by said
hanger, supplementary package-supporting
5 hooks connected to the bag, and connections
between the last-named hooks and the
hanger.

Signed at Seattle, Wash., this 2nd day of
January, 1914.

ADONIRAM J. SMITH.
